UNITED STATES PATENT OFFICE.

HARRY J. SEIBEL, JR., OF READING, PENNSYLVANIA.

APPARATUS FOR ENRICHING GAS.

SPECIFICATION forming part of Letters Patent No. 358,413, dated February 22, 1887.

Application filed October 12, 1886. Serial No. 215,985. (No model.)

To all whom it may concern:

Be it known that I, HARRY J. SEIBEL, Jr., a citizen of the United States, residing at the city of Reading, county of Berks, State of Pennsylvania, have invented a new and useful Improvement in Apparatus for Enriching Gas, of which the following is a specification.

This improvement is more particularly related to apparatus for enriching illuminating-gas with heavy hydrocarbons, volatilized by the heat of the flames of gas-burners.

The invention is fully illustrated in the accompanying vertical section of the apparatus, like letters of reference indicating similar parts.

The object of the invention is to produce a gas-enriching apparatus that is adapted to be used on board of vessels, on passenger-cars, and for street-lighting upon lamp-posts, and house-illumination generally, being applied directly to the gas-brackets, or to the supply-pipes of lamp-posts, by simply unscrewing the burners therefrom and screwing upon the same, in place thereof, the carbureting vessel or reservoir.

A represents the carbureting vessel or reservoir, which may be made of any suitable form pleasing to the eye, and has secured to its base a flange, B, threaded for attachment to the supply-pipe at B', and for connection with the stand-pipe D at B". One or more charging-tubes, B³, are suitably attached to the reservoir, and removably closed by caps B⁴.

A casing, E, is secured to the top of the reservoir, which is provided with gas-apertures E', arms E", and the usual burners, E³, with regulating-cocks E⁵. The latter may be dispensed with; but I give preference to their use, as it enables the number of burners in use to be controlled, which is of importance economically in the use of cluster-lights.

The casing is closed with a cap, E⁴, within which is secured a heating-pipe, F, projecting within the reservoir a short distance below the top of the same. The casing may, if desired, be formed as an integral piece simply threaded at the top, in which case the heating-pipe F would be secured to the same in two parts. The upper portion of the heating-pipe is swelled, as at F', to receive more fully the heat of the gas-flame G. The stand-pipe D terminates in the enlarged head F', just below

the closed top of the same, room being given so as not to interfere with the flow of gas from the main or supply pipe.

The operation of the device is as follows: The carbureting-vessel is charged with the sticks of naphthaline or other solid form of hydrocarbon through the charging-holes B³, and the caps screwed tightly down upon the same. The gas is then turned on and passing up the stand-pipe D overflows the top of the same, and descends between the pipe D and heating-pipe E, impinging upon the hydrocarbon in the reservoir, has its current reversed, as shown by the arrows, and ascends between the heating-pipe F and case E to the arms E², whence it reaches the burners E³, which are lighted. In a short time the radiating heat from the gas-flames G heats the head F' of the pipe F, which increasing the volume of the gas forces it more rapidly down upon the hydrocarbon, which is vaporized thereby, and intermingling with the gas enriches the same, producing a bright and brilliant light, the intensity of which is regulated by cocks E⁵ in the fixture, or by a cock on the main supply. (Not shown.)

I am aware of the patent to J. Livesey, No. 249,063, dated November 1, 1881, in which a carbureting-chamber is provided with a combined gas-conducting and heating pipe having a bell-shaped upper end provided with an inlet-opening for the admission of gas, said pipe extending to the bottom of the carbureting-chamber, and provided with perforations for admitting the carbureted gas into said pipe, from which it is fed to the burners, said combined heating and gas-conducting tube being divided into two sections near its upper end by a plug. A tube extends from the upper section to the lower end of the lower section, and is there provided with a suitable cock for regulating the supply of gas, the gas being conveyed to the carbureting-chamber by a curved pipe. My invention, however, is distinguished from this construction in that I admit the gas at the lower end of the carbureting-chamber, and convey it through a tube to a heating-pipe, from whence it is conveyed to the carbureting-chamber and then to the burners, thereby providing an apparatus which is much cheaper and simpler in construction than the device referred to, and at the same time thoroughly effective in operation.

I am further aware of English Patent No. 13,228 of 1884, in which a lamp is provided with a carbureting-chamber. In this patent a curved pipe extends from an inlet-opening 5 located at the lower end of the carbureting-chamber to a point above the latter, where it is bent, and then returned to the carbureting-chamber, with which it communicates, and where it is bent in a tortuous direction, and I therefore make no claim to such construction. A serious disadvantage in employing a curved induction-pipe, as described in the above patents, is found in the fact that it is liable to become clogged and prevent the free flow of gas, 15 and where the apparatus is used on railroads and vessels the flow of gas is interrupted by the swaying and jarring movement of the same.

Having shown my improvement, described 20 its advantages and construction, I desire to claim—

The combination, with a hydrocarbon-reservoir having an inlet in its lower end, and provided with a filling-opening, of a casing or chamber located on top of the hydrocarbon-reservoir, burners attached to and communicating with said casing or chamber, a heating-pipe having an enlarged head closed at its upper end, said heating-pipe extending from a point within the hydrocarbon-reservoir, near 25 the upper end thereof, through and beyond the casing E, a pipe, D, extending from the inlet-opening of the reservoir A into the heating-pipe to a point near the upper end of the latter, and a hollow plug fitting in the inlet-opening and adapted to engage the gas-bracket, 30 substantially as set forth.

HARRY J. SEIBEL, JR.
